DESIGN FOR A SHOE

Joseph Kessler, Long Island City, N. Y.

Application May 25, 1934, Serial No. 51,915

Term of patent 3½ years

To all whom it may concern:

Be it known that I, JOSEPH KESSLER, a citizen of the United States, residing in Long Island City, in the county of Queens and State of New York, have invented a new, original, and ornamental Design for a Shoe, of which the following is a specification, reference being had to the accompanying drawing, forming part thereof.

I claim:

The ornamental design for a shoe, as shown.

JOSEPH KESSLER.
